BOOK MARK

Charles H. C. Hayes, North Attleboro, Mass.

Application January 17, 1946, Serial No. 641,793

9 Claims. (Cl. 116—119)

1

My invention relates to improvements in book marks, particularly to a type of mechanical book mark which will last a long time in use, constructed of a small number of rigid durable parts adapted to be used in place of the string, ribbon, strip of fabric or leather formerly used by a reader in marking his place in a book.

I am aware that others have attempted to provide various types of mechanical book marks. So far as I am aware, these have been so complicated or so difficult in their action and hard to manipulate that they have not gone into general use. I believe I am the first to provide a book mark of the mechanical type in which in addition to the marker member, which must be flat to not spread the book too much when inserted between selected leaves when the book is in a closed position, all of the parts adapted to remain externally of the leaves in use are preferably constructed of flat sheet metal members and which comprise broadly clasp means for securing the book mark to a back binding portion of a book having a base projecting forwardly at right angles from the outer end thereof adapted to rest on adjacent ends of bound book leaves, a flat hinge member swivelably mounted on said base, a flat end plate hingedly mounted on said hinge member to pivot outwards well away from the leaves to permit them to be turned in use and a flat marker member swivelably mounted on the outer end of said end plate for insertion between selected leaves. I have visualized that in order to provide a successful mechanical book mark, all of these three relative movements are necessary in order that the marker may be moved between the leaves from cover to cover of said book and may lie between selected leaves in a plane cover parallel thereto regardless of its position in the book and that the marker and end plate may be readily and easily pivoted out of the way when not needed or as the pages are being turned. I believe I am the first therefore to provide this combination of two swivelable movements and one pivotal movement between the members of a mechanical book mark. I have also visualized that in use it is highly desirable that each of these members remain in a set position to accomplish the desired results and I therefore to make this possible have provided means in a mechanical book marker, I believe for the first time, to brake the two swivelable and one pivotal movements.

Further objects of my invention relate to the specific construction of the various means I have provided for this purpose which comprise the provision with flat members of a semi-universal joint

2

which will function through half a sphere with the braking action thereof between certain parts functioning in a horizontal plane and also between other parts functioning in a vertical plane.

5 These and such other objects of my invention as may hereinafter appear will be best understood from a description of the accompanying drawings which illustrate an embodiment thereof.

10 In the drawings:

Fig. 1 is a perspective view of my improved book mark with the end plate raised to a position raising the marker member to a position away from the leaves for standard reading purposes.

15 Fig. 2 is a perspective view of the mark shown in Fig. 1 with the end plate pivoted to a closed position.

Fig. 3 is a reverse plan view of my improved mark.

20 Fig. 4 is an exploded perspective view thereof.

Fig. 5 is a plan view of my improved book mark with the marker inserted in several positions in a book showing it in the center of the book in full lines and near each end of the book in dotted lines.

25 Fig. 6 is a perspective view of the end of a book with my book mark attached showing the marker in position between the leaves in full lines and with the end plate and marker raised to a non-reading position free of the leaves in dotted lines.

30 Fig. 7 is a vertical sectional view taken through a book with my improved marker inserted between adjacent leaves thereof.

In the drawings, wherein like characters of reference generally indicate like parts throughout, 35

10 generally indicates a book mark constructed in accordance with my invention. As shown, my invention is adapted to be used in association with a book 12 having the usual covers 14, leaves 16 and back 18. The leaves are made into folios and bound together as usual by the web or fabric 20 interposed between the inner ends 22 of the bound leaves and the back cover portion 24. In most bindings a space 26 is provided between the ends

40 22 of the leaves and the binding fabric 20 and a supplemental space 28 is provided between the binding fabric 20 and the back cover portion 24.

45 My invention comprises clasp means 30 for securing said book mark to a back binding portion of the book usually the fabric portion 20. Said clasp means 30 has a flat base 32 projecting forwardly substantially at right angles from the outer end thereof, as shown in Figs. 5 to 7 adapted to rest on adjacent ends of bound book leaves 16.

50 55 My invention also includes a flat hinge member

34 swivelably mounted on said base portion 32 and a flat end plate hingedly mounted on said hinge member 32 to pivot outwards from a position substantially in the plane thereof as shown in full lines in Fig. 6 to the dotted line position shown in Fig. 6 free of said leaves 16 and a flat marker 38 swivelably mounted on the outer end of said end plate 36.

While I preferably construct the base portion 32, the hinge member 34 and the end plate 36 out of flat stock, it is apparent that these pieces may be of any desired shape, but in as much as the marker 38 must lie in a position between adjacent leaves 16 parallel thereto, it is always constructed of flat shape. It is obvious that with this construction the flat marker 38 may swivel on said end plate 36 to lie between adjacent selected leaves from cover to cover of said book in a position parallel thereto, said end plate 36 may pivot upwards to permit movement of said flat marker 38 over a selected number of leaves 16 and said hinge member 34 may swivel on said base 32 to permit insertion of the flat marker 38 between selected leaves 16. I also provide means to brake the swivelling of the hinge member 34 on said base 32 to cause said hinge member 34 to remain in a set position, means to brake the pivotal movement of said end plate 36 on said hinge member 34 to cause said end plate to remain in a set position between or away from the leaves and means to brake the swivelling movement of said flat marker 38 to cause it to remain in a set position parallel to any particular adjacent leaves 16 in between which it may be inserted from cover to cover of said book.

In the preferable embodiment shown however, I specifically construct my improved book marker as follows: the clasp means 30 includes an L-shaped clasp member 40 having a short flat base 32 having a small hole 42 therein and a flat arm 43 projecting substantially at right angles inwardly therefrom adapted to be inserted on one side of a back binding portion, in the embodiment shown in the space 26 between the inner ends 22 of the leaves and the binding fabric 20, and a supplemental spring clip arm 44 projecting inwardly adjacent thereto to clasp the opposite side of said back binding portion 20 against said flat arm 43, in the embodiment shown said back binding portion comprising the binding fabric 20 with the spring clip 44 inserted in the space 28 between the binding fabric 20 and the back cover portion 24. The spring clip 44 first bulges outwardly as at 46 then inwardly as at 48 for clamping purposes and having below said inward bulge 48 the outwardly projecting end 50. In the embodiment shown the spring arm 44 is attached to the L-shaped member 40 as follows: Said member 40 is provided with a slot 45 substantially at the bend between said arm 43 and base 32 and the upper end of said clip member 44 is provided with a flat downwardly projecting portion 47 adapted to be inserted through said slot 45 and secured to the outer surface of said arm 40 in any suitable manner such as by the solder 49 shown. In certain books however there is not space 26 between the inner ends of the leaves and the binding fabric 20 and in this case the arm 43 is inserted in the space 28 between the binding fabric 20 or web and the back cover portion 24 and the clip arm 44 is inserted externally of the back cover portion 24 to clamp said back cover portion 24 against said arm 43.

For swivelably mounting the end plate 36 and

marker 38 on the base 32, I provide a dish shaped hinge member 34 having a flat indented circular center portion 52 having a small cylindrical extension 54 projecting downwardly therefrom through said hole 42 in said clasp base 32 and having its end radially outturned as at 56 to abut the lower surface thereof. It is obvious that this construction causes the indented portion 52 of said hinge member 34 to frictionally abut said base 32 to brake the swivelling movement of said hinge member thereon and cause it to remain in a set position as well as swivelably mounting said hinge member 34 on said base 32. Said hinge member 34 also has an outer annular portion 58 having diametric upwardly looped hinge ear forming portions 60. The flat end plate 36 is provided with a circular indented portion 62 near the outer end thereof having a central hole 64 therein and an extension 66 projecting inwardly from the inner end thereof of a width substantially the diameter of said indented portion 52 of the hinge member 34 rolled over on itself into the cylindrical hinge ear 66. The hinge pin 68 is thus inserted through the upwardly projecting loops 60 and hinge ear 66 so that its center portion extends through said cylindrical hinge ear 66 and its ends are interposed between the ear loops 60 on said hinge member and said clasp member base 32 so that said cylindrical plate ear 66 may frictionally abut the indented base 52 of said hinge member 34 to brake the pivoting movement of said end plate and to cause it to remain in a set position such as the raised position shown in dotted lines in Fig. 6.

It is thus apparent that this particular construction provides a universal joint of universal movement throughout half a sphere with the braking action shown on the horizontal component thereof and also on the vertical component thereof.

I provide a circular washer 70 having an elongated slot 72 centrally thereof resting in said indented portion 62 in said end plate 36 and I provide a flat book marker 38 with a narrow portion 74 projecting upwardly through said hole 64 in said circular end plate indentation 62 and said slot 72 in said washer 70 having its upper end downturned as at 76 as shown in Figs. 5 and 7 over said washer 70 so that said flat marker 38 may turn with said washer 72 to cause it to abut said indented portion 62 and the upper edge 78 of said marker to abut the lower surface of said indented portion 62 to brake the swivelling movement of said flat marker 38 and to cause it to remain in a set position between the leaves.

In use, my improved book mark has the clasp portion 30 inserted to clasp the binding fabric 20 or the back cover portion 24 as shown in Figs. 5 to 7. The reader then pivots the end plate 36 and flat marker 38 to the dotted line position shown in Fig. 6 free of the leaves 16 and when he desires to leave the book pivots it down to the position shown in full lines in Fig. 6 between the leaves and it is obvious that the joint for swivelling movement between the hinge member 34 and base 32 permits the end plate and marker 38 to swivel laterally and the joint between the marker 38 and end plate permits the marker 38 to pivot laterally to permit the flat mark 38 to be inserted between any selected leaves 16 from cover to cover 15.

In the embodiment shown I have shown the stop lugs 80 on the lower surface of the indented

portion 62 of said end plate 36 exterior of said hole 64 to limit the swivelling movement of said marker 38 to permit it to only swivel an amount sufficient so that it may be inserted between any selected leaves from cover to cover 14 of the book. If desired, however, those stop lugs 80 may be omitted and the end plate 36 moved to a position substantially parallel to said arm 43 on opening of the book to cause the leaves to remain in a set position with the book open. When the user is through with the book mark 10 it is obvious that he may readily detach the clasp means 30 from the book.

It is apparent that I have provided a novel type of book mark with the advantages explained above.

It is understood that my invention is not limited to the specific embodiment shown and that various deviations therefrom may be made without departing from the spirit and scope of the appended claims.

What I claim is:

1. A book mark, comprising clasp means for securing said book mark to a back binding portion of a book having a flat base portion projecting forwardly substantially at right angles from the outer end thereof adapted to rest on adjacent ends of bound book leaves, a flat hinge member swivelably mounted on said base portion, said swivelable mounting causing said hinge member to remain in a set position, a flat end plate hingedly mounted on said hinge member to pivot outwards from a position substantially in the plane thereof abutting the ends of said bound leaves, said hinged mounting causing said end plate to remain in a set position and a flat marker swivelably mounted on said end plate, said swivelable mounting causing it to remain in a set position whereby said flat marker may swivel on said end plate to lie between adjacent selected leaves from cover to cover of said book in a position parallel thereto, said end plate may pivot upwards to permit movement of said flat marker over a selected number of leaves, and said hinge member may swivel to permit insertion of the flat marker between selected leaves.

2. A book mark comprising clasp means for securing said book mark to a back binding portion of a book having a flat base portion projecting forwardly substantially at right angles from the outer end thereof, a flat hinge member swivelably mounted on said base portion, said swivelable mounting causing said hinge member to remain in a set position, a flat end plate hingedly mounted on said hinge member to pivot outwards from a position substantially in the plane thereof, said hinged mounting causing said end plate to remain in a set position and a flat marker swivelably mounted on said end plate, said swivelable mounting causing it to remain in a set position.

3. A book mark comprising clasp means for securing said book mark to a back binding portion of a book having a base portion projecting forwardly substantially at right angles from the outer end thereof adapted to rest on adjacent ends of bound book leaves, a flat hinge member swivelably mounted on said base portion, a flat end plate hingedly mounted on said hinge member to pivot outwards from a position substantially in the plane thereof abutting the ends of said bound leaves, and a flat marker swivelably mounted on said end plate whereby said flat marker may swivel on said end plate to lie between adjacent selected leaves from cover to cover of said book

5 in a position parallel thereto, said end plate may pivot upwards to permit movement of said flat marker over a selected number of leaves, and said hinge member may swivel to permit insertion of the flat marker between selected leaves.

4. A book mark comprising clasp means for securing said book mark to a back binding portion of a book having a base portion projecting forwardly substantially at right angles from the outer end thereof adapted to rest on adjacent ends of bound book leaves, a hinge member swivelably mounted on said base portion, an end plate hingedly mounted on said hinge member to pivot outwards from a position substantially in the plane thereof abutting the ends of said bound leaves, and a flat marker swivelably mounted on said end plate whereby said flat marker may swivel on said end plate to lie between adjacent selected leaves from cover to cover of said book in a position parallel thereto, said end plate may pivot upwards to permit movement of said flat marker over a selected number of leaves, and said hinge member may swivel to permit insertion of the flat marker between selected leaves.

5. A book mark comprising clasp means for securing said book mark to a back binding portion of a book having a flat base portion projecting forwardly substantially at right angles from the outer end thereof, a flat hinge member swivelably mounted on said base portion, a flat end plate hingedly mounted on said hinge member to pivot outwards from a position substantially in the plane thereof, and a flat marker swivelably mounted on said end plate.

6. A book mark comprising clasp means for securing said book mark to a back binding portion of a book having a base portion projecting forwardly substantially at right angles from the outer end thereof, a hinge member swivelably mounted on said base portion, an end plate hingedly mounted on said hinge member to pivot outwards from a position substantially in the plane thereof, and a flat marker swivelably mounted on said end plate.

7. A book mark comprising an L-shaped clasp member having a short flat base adapted to rest on adjacent ends of bound book leaves having a small hole therein, a flat arm projecting substantially at right angles inwardly therefrom on one side of a back binding portion and a supplemental spring clip arm projecting inwardly adjacent thereto to clasp the opposite side of said back binding portion against said flat arm, a flat dish shaped hinge member having a flat indented circular center portion having a small cylindrical extension projecting downwardly therefrom through said hole in the clasp base and having its end radially outturned to abut the lower surface thereof to swivelably mount said hinge member on said clasp base portion so that the indented portion of said hinge member may frictionally abut said base to brake the swivelling movement of said hinge member thereon and cause it to remain in a set position, and an outer annular portion having diametric upwardly looped hinge ear forming portions, a flat end plate adapted to abut the ends of said bound leaves having a circular indented portion near the outer end thereof having a central hole therein, and an extension projecting inwardly from the inner end thereof of a width substantially the diameter of said indented portion of the hinge member rolled over on itself into a cylindrical hinge ear, a hinge pin having its center portion extending through said cylindrical

hinge ear and its ends interposed between the ear loops on said hinge member and said clasp member base so that said cylindrical plate ear may frictionally abut the indented base of said hinge member to brake the pivoting movement of said end plate and cause it to remain in a set position; a circular washer having an elongated slot centrally thereof resting in said indented portion in said end plate and a flat marker adapted to be interposed between selective leaves of the book having a narrow portion projecting upwardly through said hole in said circular end plate indentation and said slot in said washer having its upper end downturned over said washer so that said flat marker may turn with said washer to cause it to frictionally abut said indented portion to brake the swivelling movement of said flat marker and cause it to remain in a set position between the leaves.

8. A book mark comprising an L-shaped clasp member having a short flat base having a small hole therein, a flat arm projecting substantially at right angles inwardly therefrom and a supplemental spring clip arm projecting inwardly adjacent thereto, a flat dish shaped hinge member having a flat indented circular center portion having a small cylindrical extension projecting downwardly therefrom through said hole in the clasp base and having its end radially outturned to abut the lower surface thereof to swivelably mount said hinge member on said clasp base portion so that the indented portion of said hinge member may frictionally abut said base to brake the swivelling movement of said hinge member thereon and cause it to remain in a set position, and an outer annular portion having diametric upwardly looped hinge ear forming portions; a flat end plate having a circular indented portion near the outer end thereof having a central hole therein, and an extension projecting inwardly from the inner end thereof of a width substantially the diameter of said indented portion of the hinge member rolled over on itself into a cylindrical hinge ear, a hinge pin having its center portion extending through said cylindrical hinge ear and its ends interposed between the ear loops on said hinge member and said clasp member base so that said

cylindrical plate ear may frictionally abut the indented base of hinge member to brake the pivoting movement of said end plate and cause it to remain in a set position, a circular washer having an elongated slot centrally thereof resting in said indented portion in said end plate and a book marker having a narrow portion projecting upwardly through said hole in said circular end plate indentation and said slot in said washer having its upper end downturned over said washer so that said flat marker may turn with said washer to cause it to frictionally abut said indented portion to brake the swivelling movement of said flat marker and cause it to remain in a set position between the leaves.

9. A book mark comprising a clasp member having a short flat base having a small hole therein; clasp means projecting downwardly therefrom for securing said book mark to a back binding portion of a book, a flat dish shaped hinge member having a flat indented circular center portion having a small cylindrical extension projecting downwardly therefrom through said hole in the clasp base and having its end radially outturned to abut the lower surface thereof to swivelably mount said hinge member on said clasp base portion so that the indented portion of said hinge member may frictionally abut said base to brake the swivelling movement of said hinge member thereon and cause it to remain in a set position, and an outer annular portion having diametric upwardly looped hinge ear forming portions; a flat end plate having an extension projecting inwardly from the inner end thereof of a width substantially the diameter of said indented portion of the hinge member rolled over on itself into a cylindrical hinge ear; a hinge pin having its center portion extending through said cylindrical hinge ear and its ends interposed between the ear loops on said hinge member and said clasp member base so that said cylindrical plate ear may frictionally abut the indented base of said hinge member to brake the pivoting movement of said end plate and cause it to remain in a set position, a flat marker and means to swivelably mount said flat marker on the outer end of said end plate.

CHARLES H. C. HAYES.
